United States Patent Office.

SAMUEL AYRES, OF DANVILLE, KENTUCKY.

Letters Patent No. 94,270, dated August 31, 1869.

IMPROVEMENT IN FASTENINGS FOR BREASTPINS.

The Schedule referred to in these Letters Patent and making part of the same.

To all whom it may concern:

Be it known that I, SAMUEL AYRES, of Danville, in the county of Boyle, and State of Kentucky, have invented a new and improved Pin-Catch for Breastpins, and similar articles; and I do hereby declare that the following is a full, clear, and exact description thereof, which will enable others skilled in the art to make and use the same, reference being had to the accompanying drawings, forming part of this specification, in which—

Figure 1 represents an inverted plan view of a breastpin provided with my improved pin-catch.

Figure 2 is an edge view of the same.

Figure 3 is an edge view of a modification of the same.

Similar letters of reference indicate corresponding parts.

This invention has for its object to so construct breastpins, and other similar articles, such as badges, &c., that they can be secured to garments by means of an ordinary pin, in a secure manner, and with great convenience.

Breastpins as now made are provided with pins, which are inconvenient to apply, and which are apt to break or become dull, or bent, while by my invention, a common pin can be used, and when bent or worn, may be readily replaced by another.

The invention consists in the use of a hook, spring, and catch, which are arranged on the under side of the breastpin, in such manner that the desired object will be obtained.

A, in the drawing, represents the body of a breastpin.

From the under side projects a hook-shaped plate, a, which has its lower arm flared out to facilitate the application of a pin.

b is a small lever, pivoted to a lug, c, that projects from A, and held by a spring, d, of suitable description, opposite the slot of the plate a, as shown.

e is an eye, projecting from the body A.

A pin, B, can, with its point, be fitted through the

eye e, while its upper part is pushed into the hook a, snapping over the lever b d, so that it will be held by the said lever b in the hook.

Longitudinal displacement of the pin is in one direction prevented by its head, which strikes against the hook a, and in the other direction by a plate, f, projecting from the body A.

The device is applied by first putting the pin into the garment, then drawing the eye e over its point, and then, by lateral motion, forcing the hook over it.

When to be released, the catch b is swung so as to open the slot of a, when the breastpin is free to be taken off.

The outer end of the lever should be in such a position that it can conveniently be reached to open the hook, and it may, for this reason, be either extended beyond the side of the body, as in fig. 2, or it may be turned up on narrow pins, as in fig. 3.

I am aware that an English patent exists, where a device is shown which has the same object, and in some parts presents a similar aspect to mine, but the similarity is more in appearance than reality, since the combination and arrangement of parts to secure the same results are materially different. The device exhibited in that case is manifestly ill adapted to its purpose, and inoperative in practice. However, I do not desire to claim broadly any device which will accomplish the same end; but

What I do claim as of my invention, and desire to secure by Letters Patent, is—

1. The combination of the pivoted lever b and spring d and hook B a, the said parts being each constructed and arranged with reference to one another, as shown and described.

2. The combination of the said lever, spring, and hook with the stay f and eye e, on the breastpin, as and for the purpose specified.

SAML. AYRES.
